COOLING UNIT

Burdell S. Williams, Dayton, Ohio, assignor to
 Chrysler Corporation, Detroit, Mich., a corpora-
 tion of Delaware

Application July 30, 1942, Serial No. 451,569

1 Claim. (Cl. 62—129)

My present invention relates to the arts of air conditioning and refrigeration.

The object of my present invention is to provide a portable completely operative unit for cooling and/or dehumidifying air in the enclosure to which the unit may be applied. The invention comprises a panel member adapted to form a detachable section of a wall of the enclosure to which the unit is to be applied, and a completely assembled refrigeration system mounted on said panel, preferably in combination with means to circulate air over the evaporator surfaces of the refrigeration system rather than to depend upon natural draft circulation. The completely assembled refrigeration system comprises condensing equipment mounted on the side of the panel adapted to form a portion of the exterior surface of the enclosure to which the unit is applied and evaporating and air handling equipment mounted on the opposite side of the panel which is adapted to form a portion of the interior surface of the enclosure, said condensing equipment being thus readily accessible for service when the panel is assembled with a wall of the enclosure and said evaporating and air handling equipment being exposed to the interior of the enclosure when the panel is assembled with a wall of the enclosure. The overall dimensions of the evaporating and air handling equipment are lesser than the overall dimensions of the panel so that the unit may be readily associated with or disassociated from an enclosure and another unit substituted therefor in order that servicing of a damaged unit may be accomplished without interruption of the refrigeration or cooling of the interior of the enclosure.

The purpose of the present invention is to provide portable refrigeration or air conditioning equipment which may be placed in operation at remote points, particularly in regions where mechanics and artisans are not available. Thus the present invention may be flown into inaccessible gold mining camps in jungles and immediately placed in operation by connecting the unit to power generating equipment. Other possible uses might include the air conditioning of advanced base military hospitals, advanced base food storage depots, temporary encampments, the transportation of perishable commodities on ships not primarily designed for cold storage, and many other similar purposes.

A further object in providing the present invention is to provide a unit which may be quickly replaced while damaged or broken portions of the unit are being repaired, either in the field or

at the factory. Thus the present invention eliminates the necessity for maintenance of a repair crew and large stocks of replacement parts at advanced bases.

5 These and other objects and advantages of the present invention may be more fully appreciated from a study of the following specification taken in connection with the accompanying drawings wherein several modifications of the present invention are disclosed.

In the drawings, Fig. 1 is a plan view of a preferred form of the invention;

Fig. 2 is a side elevation of the apparatus disclosed in Fig. 1;

15 Fig. 3 is an enlarged side view of the opposite side of the apparatus disclosed in Fig. 1, and showing some details of the internal arrangement of the apparatus;

Fig. 4 is a front view of the apparatus taken 20 from the outside of the enclosure, with the cover of the condensing compartment removed in order to show details of the refrigeration system;

Fig. 5 is a view in perspective of a modified form of the invention;

25 Fig. 6 is a view in perspective of the opposite side of the apparatus disclosed in Fig. 5;

Fig. 7 is a view in perspective of the apparatus of Fig. 5 as it might be crated for shipment;

30 Fig. 8 is a schematic horizontal section through an enclosure such as a knock-down meat cooler with a unit manufactured in accordance with the present invention mounted in one side of the enclosure;

Fig. 9 is a similar view showing the unit at the 35 back of the enclosure;

Fig. 10 is a similar view showing the unit at the opposite side of the enclosure;

Fig. 11 shows how a large storage cooler, or a 40 number of rooms for different purposes such as storage, hospitalization, chemical processing, or photographic laboratories, or the like, may be provided by joining a number of detachable knock-down wall sections with a unit of the present invention associated with each room of the assembly;

Fig. 12 is a front view of the condensing compartment of a further modification of the present invention;

Fig. 13 is a partial plan view of the apparatus 50 shown in Fig. 12; and

Fig. 14 is a side elevation of the apparatus disclosed in Fig. 12.

Referring to Figs. 1 to 4, inclusive, there is disclosed a unit comprising a panel 10 preferably formed by connecting vertical timbers 13 and 14

to horizontal timbers 15 and 16 and fastening metallic plates or plywood panels 17 and 18 to the rectangular frame so formed. The interior space between the frame and the side panels is preferably packed with an insulating material 19 such as mineral wool or the like. The panel is adapted to form a detachable section of the wall of an insulated enclosure such as by fastening the panel to wall sections 20, 21 and 22, as by means of detachable brackets 23 and bolts 24.

The panel 10 provides means to mount a condensing compartment 25 and an evaporating compartment 26 in which are housed the appropriate portions of the refrigerating and air handling equipment so that when the panel is mounted in the enclosure wall and power connected to the motors of the unit refrigeration may be immediately accomplished, as distinguished from the prior practice of assembling the various portions of the apparatus by means of pipes, dehydrating the apparatus, charging the apparatus with refrigerant and oil, wiring and adjusting the various controls, and in general providing skilled supervision.

The condensing compartment comprises any means for compressing and cooling a refrigerant. A suitable form of equipment is illustrated, it being readily apparent that other forms of apparatus for accomplishing the function may be substituted therefor. In the disclosure a compressor 30 having a motor hermetically sealed therein is suspended from brackets 31 and 32 attached to the frame of a suitable housing in which the compressor is enclosed. Refrigerant gas compressed by the compressing mechanism is discharged into an oil separator 33 from which oil separated from the refrigerant gas is returned to the compressor through tube 34. The gas then passes through a discharge pipe 35 leading to the various tubes of a finned coil condenser 36 mounted horizontally across the top of the casing. The refrigerant is cooled and liquefied in the condenser and collected in an accumulator 37 from which a tube 38 leads to a liquid receiver 39 mounted in the bottom of the condensing unit casing. Liquid may be drawn off from the liquid receiver through a tube 40 connected to a pipe 41 passing through the panel 10 into the evaporating compartment 26. Suitable control means such as solenoid valve 42, thermal expansion valve 43, and distributor 44 may be provided to properly regulate the passage of refrigerant through the various tubes of a finned evaporator coil 45 located in the lower portion of the evaporating compartment. The expanded refrigerant vapor which has been warmed by the absorption of heat from the air passing over the coil 45 is collected in the manifold 46 and returned to the compressor through a suction pipe 47 passing through the panel 10.

When the unit is in operation a forced circulation of air is preferably created in the evaporating compartment by means of a blower wheel 50 driven by a motor 51 connected thereto through pulleys 52 and 53 and a belt 54, the blower wheel being enclosed in an involute housing 55 having its open mouth 56 extending upwardly through the top of the casing of the evaporator compartment. Air may be drawn into the compartment through an opening 57 in a side wall of the casing of the evaporator compartment located below the coil 45, to which a return duct may lead if desired, and the air may be discharged directly into the enclosure or may be discharged into a duct or deflecting vane assembly, depending upon the distribution desired.

The cooling of the refrigerant in the condenser coil 36 may be accomplished in any of the usual manners, that illustrate comprising a pair of air propellers 60 driven by motors 61, the motors being mounted upon brackets 62 and the propeller blades being mounted adjacent openings through the side wall of the casing of the condensing compartment so that air is forced around the compressor and through the interstices of the condenser coil. The condensing compartment is preferably closed by means of a removable front panel having locking handles 63 thereon through which access to the compressor may be had. Preferably gauges such as suction pressure gauge 64, oil pressure gauge 65, and discharge pressure gauge 66, are mounted in front of the condenser coil so as to be at a convenient height, and are connected by tubing to the respective portions of the compressor so that the operation of the compressor may be determined without removing the front panel.

Preferably the walls of the evaporating compartment casing and the condensing compartment casing adjacent the panel 10 are fastened thereto as by means of bolts 70 extending through the panel so as to provide a rigid structure. Also, the bottoms of the compartments and the bottom of the panel may be fastened to angle bar rails 71 having protruding ends provided with holes 72 by means of which the unit may be attached to a hoisting sling or attached to a foundation of wood or concrete.

The modification disclosed in Figs. 5, 6 and 7 comprises a panel 80 composed of a central double-walled, insulated wall 81 having flanges 82 at its edges, the flanges being provided with holes 83 by means of which the panel may be bolted to other wall sections to form an enclosure. A condensing machinery compartment 85 is mounted on one side of the panel and an evaporating machinery compartment 86 is mounted on the opposite side of the panel, the refrigerant being led from one compartment to the other through pipes 87 and 88 passing through the panel wall portion 81. The panel and the machinery compartments are preferably permanently attached to a foundation 90 provided with skids 91 for facilitating movement of the unit. Since the panel in this case is so much larger than the evaporating compartment an external motor 92 may be provided to drive blower wheels 93 (one shown) through an external belt 94 and pulleys 95 connected to a shaft 96 extending through the compartment and to which the blowers are fastened. Air may be drawn into the evaporating compartment through the entrance 97 and discharged through the outlet openings 98, which in this case extend horizontally forward.

Fig. 7 discloses how the unit may be enclosed in a crate 100 comprising a top portion 101 which may be bolted to the flanges 82 at the top of panel 80 and vertical boards 102 which may be fastened to the top portion 101 and the base 90 and skids 91. It is, of course, obvious that the other modifications may be similarly crated for shipment to the point of use or reshipment to a servicing center.

Figs. 8, 9 and 10 show how the units of the type disclosed may be placed in a side wall or rear wall of a single enclosure or in various portions of a multiple room enclosure. In these schematic views the evaporating portion of the unit is indicated by the numeral 105 and the condensing portion, which is exteriorly located and available for minor service problems, is in-

dicated by the numeral 106. It is to be appreciated that in each of these views a portion of the wall of the enclosure is formed by the panel of the unit, and that the overall dimensions of the evaporating compartment 105 are lesser than the overall dimensions of the panel portion so that the unit may be inserted or withdrawn as a whole.

The modification disclosed in Figs. 12, 13 and 14 comprises a panel portion 110 adapted to be suitably attached to wall portions 111 and 112 of an enclosure with which the unit is to be associated, an evaporating compartment 113 mounted at a height above the bottom of the unit, and a condensing compartment 114 mounted on the opposite side of the panel. This unit comprises a central compressor-containing portion having a removable door 115 provided with a knob 116, a lower tool compartment 117 provided with a hinged door 118, and an upper blower motor-containing compartment 119. Air is adapted to be drawn through the condenser coil 120 by means of propellers 121 attached to motors 122 in compartment 119 and discharging outwardly through a hinged hood 123, the hood forming in effect a continuation of the top cover 124. The hood 123 is provided with a series of holes 125 through which an adjusting pin 126 may be passed to regulate the position of the hood so as to control the amount of air flowing over the condenser and to permit closing of the blower compartment when not in use. The air is drawn into the compressor compartment through a series of louvers 127 in the side walls of the compressor compartment. The whole assembly is preferably mounted on an angle iron skid frame 128 provided with hoisting rings 129.

The evaporating compartment comprises a coil 130 over which air is drawn by blower wheel 131 discharging into a plenum chamber 132 adapted to deflect the discharge horizontally forward. The air may be drawn into the coil through a lower collecting chamber 133.

Suitable adjuncts not herein fully illustrated may be provided; as, for example, defrosting sprayers 134 (Fig. 14) may be provided to par-

ticularly defrost the evaporator coil, and the same may be connected to a source of water through a tube 135 extending through the mounting panel as shown in Fig. 6.

- 5 It is also to be appreciated that other types of refrigerating systems may be substituted for the mechanical system illustrated, many such systems being known to those skilled in the art.
- 10 It should be obvious to those skilled in the art that many modifications in arrangement and detail may be provided within the teachings of my invention. All such modifications as come within the scope of the following claim is considered a part of my invention.

I claim:

A portable self-contained refrigerating apparatus adapted to be assembled in and through an aperture formed in a wall of an enclosure 20 to be cooled, comprising a rectilinear panel having front and back walls spaced by heat insulating material, a base under said wall and extending at right angles thereto from both the front and back walls to provide an inverted T 25 framework, an air cooling member positioned on the front wall of the panel wholly within the marginal confines thereof and above said base, said cooling member including a substantially rectilinear housing extending over the adjacent portion of said base, said housing being formed with an upper section, a blower mounted in said upper section, an evaporating coil mounted in the housing below the blower, duct means formed in the housing to admit 30 air below the coil for discharge at the upper section of the blower, a second housing positioned on the back wall of the panel and above its adjacent base, a refrigerant compressor and condenser mounted on the second housing, air flow inducing means mounted on said second housing, and piping interconnecting the evaporator, compressor and condenser through said panel to establish a refrigerating circuit therebetween.
